UNITED STATES PATENT OFFICE.

FRANK HINMAN PIERPONT, OF HORLEY, ENGLAND, ASSIGNOR TO LANSTON MONOTYPE MACHINE COMPANY, OF PHILADELPHIA, PENNSYLVANIA, A CORPORATION OF VIRGINIA.

MATRIX-CASE EQUIPMENT FOR TYPOGRAPHIC MACHINES.

Application filed February 19, 1924. Serial No. 693,854.

To all whom it may concern:

Be it known that I, FRANK HINMAN PIERPONT, a citizen of the United States of America, residing at Salfords, Horley, in the 5 county of Surrey, England, have invented certain new and useful Improvements in Matrix-Case Equipments for Typographic Machines; and I do hereby declare the following to be a full, clear, and exact description of the same, reference being had to the accompanying drawings, forming part of 10 this specification, and to the characters of reference marked thereon.

This invention relates to matrix or die 15 case equipment for type casting and similar typographic machines and refers to matrix cases in which the matrices are assembled in a frame in rows and columns. A matrix case of the kind referred to, as well as a 20 machine in which it is adapted to be employed, is basically disclosed in United States Letters Patent No. 625,998, dated May 30, 1899. In such a matrix case the 25 matrices are oblong blocks, rectangular in cross section, one end being furnished with a character or formative cavity and the other end with a centering cavity usually conical in shape for engagement with a centering device for clamping and pressing 30 each matrix against the mold when a cast is to be made. In the patented matrix case, the 35 matrices are provided with lateral holes through their bodies for the accommodation of suspension rods, the construction being such that each rod suspends or supports a 40 row of matrices. While these rods limit to some extent the lateral movements of the matrices of a row in one direction, they allow in the other direction the accumulated 45 wear of a column of matrices to result in the displacement of any matrix of that column to a harmful extent. They also permit matrices to turn or tilt in an undesirable manner.

The main object of the present invention 50 is to provide means for limiting the side motion of an individual matrix in a direction parallel to the supporting rods which pass through the openings in the bodies of the matrices; and to so construct the matrices and supporting bars therefor that a matrix or matrices can be removed and replaced without disturbing or interfering with the other matrices of the series. This

is accomplished in accordance with the 55 present invention by the use of two series of parallel suspension bars or rods arranged at right angles to each other and having their ends resting in openings in the matrix case frame, through which openings the 60 bars or rods may be inserted or withdrawn. Conveniently the rods or bars of a series are all secured to a common plate or bar so that they can be manipulated as a single 65 piece. Moreover, one series of bars serves 70 to lock the other in position and a locking device is mounted on the matrix case to lock the other series against accidental displacement. Other objects will be hereinafter 75 pointed out or will otherwise appear in connection with the description of the invention as embodied in the accompanying drawings in which

Fig. 1 is an inverted plan view of a matrix case embodying the present invention. 75

Fig. 2 is a vertical section on approximately line 2-2 of Fig. 1,

Fig. 3 is a vertical section on approximately line 3-3 of Fig. 1,

Fig. 4 is a bottom plan view of one set 80 of suspension bars,

Fig. 5 is an end view of the set of bars shown in Fig. 4,

Fig. 6 is a plan view of the second set of 85 suspension bars,

Fig. 7 is an end view of said second set of bars,

Fig. 8 is an end elevation of one of the 90 matrices, and

Fig. 9 is an elevation of a matrix viewed 95 in a direction at right angles to that shown in Fig. 8.

The matrix case comprises a frame 1 of usual and well-known construction being box-like and having an opening through it 95 for the accommodation of the matrices. On the top of the frame 1 is a cover plate 2 provided with a series of perforations or openings 3 coinciding, when the matrices are 100 assembled in the matrix case, with the centering cone holes 4 in the matrices 5 (Fig. 2).

The matrices 5 are oblong blocks, rectangular in cross section and furnished as 105 hitherto with a character or formative cavity 6 in one end and a conical centering cavity 4 in the other end. In Fig. 1 for the sake of clearness, the character cavities have

been omitted. For accommodating the suspension devices the matrices are conveniently provided or furnished on two of their exterior walls with transverse external parallel grooves 7; and at right angles to these grooves each matrix has a central transverse suspension opening 8 therethrough.

The two end walls of the matrix case are furnished with a series of openings 9, 10, 10 and the suspension rods 11 are passed through the openings 9 and their inner ends caused to rest in the openings 10. The openings 9, 10 are in line with the central openings 8 in the various rows of matrices 15 when the latter are assembled in the matrix case frame 1, so that each bar 11 passes through the central openings of a row of matrices (Fig. 3). The bars 11 thus limit 20 and control the lateral movement of the row of matrices in a direction at right angles to the said bars 11.

The two side walls of the matrix case frame 1 are furnished with openings 12, 13 and the suspension bars 14 are passed 25 through the openings 12, their inner ends resting in the openings 13. Each bar 14 passes between the matrices of two neighboring columns and is accommodated in the external grooves 7 in the sides of the matrices 30 of two neighboring rows or columns (Fig. 2). The bars 14 are approximately of a thickness or width equal to the depths of the grooves in the two matrices which they support. These bars 14 limit the lateral movements 35 of the matrices in a direction at right angles to that controlled by the bars 11.

The method of suspension above described prevents the accumulated wear of a row or column of matrices from allowing a single matrix to become displaced to such an extent as to place it out of register with the corresponding opening 3 in the protector plate 2, or so that the centering cavity 4 of the matrix cannot be entered by the usual centering device. The openings 9, 10 are on a different horizontal plane from the openings 12, 13, and the bars 11 and 14, which are conveniently round, are furnished or formed on their meeting sides with flattened parts 50 15, 16 (Figs. 4 to 7). The flat portions of the bars 11 and 14 thus bear upon each other and provide a rigid support for the matrices.

In order to allow of the requisite vertical movement of a matrix relatively to the others when a cast is being made, the bars 11 and 14 are of slightly smaller diameter than the openings 8 and grooves 7.

For convenience in removing all the bars 60 of a series together, the outer ends of the bars 11 are connected to or mounted in a plate or connecting bar 17 (Fig. 4) which in assembled position lies close against one end of the matrix case frame and is retained 65 there by a suitable locking spring 18. One

end of the spring 18 is secured to an existing extension of the matrix case frame 1 and its free end bears against the plate 17. The plate 17 is furnished with a notch 19 to receive the spring 18 when the latter has been depressed and thus allow the bar 17 and rods 11 to be removed.

Similarly, the bars 14 are all connected to a plate 20 which, when the bars have been inserted into the holes 12 in the frame, lies close against one side member of the matrix case. On the upper surfaces of the bars 14 are formed shoulders 21 one pair to each bar, these shoulders being formed by interrupting the cutting of the flat surfaces 16, and one of the bars 11 passes between these shoulders and thus locks the entire series of bars 14 in position.

When it is required to remove a matrix or matrices, the locking spring 18 is depressed and the bar 17 pulled away to withdraw the bars 11. This releases the bars 14 and the plate 20 and they may next be withdrawn. This removal of both series of bars frees the matrices anyone of which may be removed separately from the matrix case in an obvious manner.

I claim:

1. A matrix case comprising a frame, a series of matrices therein arranged in rows and columns, two series of suspension bars extending at right angles to each other to support the matrices and limit lateral movements of individual matrices, each series of bars being supported in openings in the said frame, extending lengthwise of the bars whereby each series of bars may be withdrawn or inserted in a direction lengthwise of the bars thereof through the frame openings therefor.

2. A matrix case comprising a frame, matrices therein having external side suspension grooves and transverse central suspension openings at right angles to said grooves, two series of suspension bars supported in the frame at right angles to each other and engaging respectively the grooves and openings in the matrices and a connecting bar secured to each series of suspension bars.

3. A matrix case comprising a frame, matrices therein having external side suspension grooves and transverse central suspension openings at right angles to said grooves, two series of suspension bars supported in the frame at right angles to each other and engaging respectively the grooves and openings in the matrices and a connecting bar secured to each series of suspension bars, one series of bars being provided with locking shoulders to engage with one bar of the other series, whereby one series is locked by the other, and means for locking the last mentioned series in the said frame.
